UNITED STATES PATENT OFFICE

RAYMOND B. MEYER, OF WASHINGTON, DISTRICT OF COLUMBIA, ASSIGNOR, BY MESNE ASSIGNMENTS, TO WIRED RADIO, INC., OF NEW YORK, N. Y., A CORPORATION OF DELAWARE

ELECTRON TUBE TRANSMITTER

Application filed March 16, 1927. Serial No. 175,757.

My invention relates broadly to signal transmission systems and more particularly to a circuit arrangement for an electron tube transmitter having its circuits supplied with power from an alternating current source.

One of the objects of my invention is to provide an electron tube circuit arrangement for high frequency signal transmitting systems where power is obtained for exciting the electron tube circuits from an alternating current source with special means for preventing parasitic oscillations in the electron tube circuits.

Another object of my invention is to provide a balanced high frequency oscillator, intermediate amplifier and power amplifier circuit system for signal transmitters with means for dephasing and cancelling current components which would normally tend to establish undesired oscillations in the tube circuits for stabilizing the operation of the transmitter.

My invention will be more fully understood from the specification hereinafter following by reference to the accompanying drawing which diagrammatically illustrates an electron tube transmission circuit embodying the principles of my invention.

The transmission circuit involves a bi-lateral arrangement of sets of tubes connected as oscillators, frequency multipliers and high frequency amplifiers.

In the drawing 12 is an inductance in the plate circuit of a set of tubes which may be considered as the master oscillator circuit. C3 is a by-pass condenser by means of which radio frequency energy is applied to the grids of tubes 3 and 4, which may be considered as the intermediate amplifier circuit. The intermediate amplifier circuit may be arranged to operate as a frequency doubler for increasing the frequency of the master oscillator circuit. C4 and C4' are radio frequency by-pass condensers in the plate circuits of the tubes in the intermediate amplifier. 14 is an inductance which may be tuned to the proper frequency by means of the variable condenser B which is shunted around the inductance. A2 is a radio frequency ammeter used for determining the condition of resonance. It will

be noted that 14 has a connection at the center of the coil which connects to the filaments of the vacuum tubes and that the connections from the plate by-pass condensers C4 and C4' are arranged symmetrically on either side of the ground or filament connection.

The grids of the tubes 5 and 6, which may be considered as the tubes in the power amplifier circuit, are energized by means of taps taken off the inductance 14 through the grid by-pass condensers C6 and C6'. Again it will be noted that these taps are connected to the inductance 14 symmetrically on either side of the filament or ground point. C7 and C7' are radio frequency by-pass condensers in the plate circuits of the power amplifier tubes, 5 and 6 by means of which energy is transferred to the inductance 15.

The purpose of a balance is to neutralize the effect of coupling resulting from the inter-element capacity in the vacuum tubes. The balance is obtained in the following manner. The radio frequency energy being transferred from the inductance 12 through the by-pass condenser C3 is employed to energize the grids of tubes 3 and 4. It is desirable and necessary that this energy be confined to accomplishing this function alone and that no appreciable amount of radio frequency be fed through the capacities between grid and plate which would have the effect of coupling the intermediate amplifier circuit to the master oscillator circuit which would result in reactions and other deleterious effects.

It is understood that tube 3 operates during one-half of a cycle while tube 4 operates during the other half of the cycle for amplifying the high frequency oscillations supplied by the oscillator system. The inter-element capacities in both tubes being approximately equal and the amount of inductance in the plate circuits of each tube being approximately equal and on opposite sides of the filament connection, it will be seen that the radio frequency energy by-passed by the tubes will be of approximately equal magnitude and 180 degrees out of phase so that the magnetic fields set up in inductance 14 will cancel each other, resulting in no flow of current. Thus the effect of the inter-element capacities and

the coupling resulting therefrom is neutralized. Therefore, no energy will be fed over from the master oscillator circuit into the intermediate amplifier circuit, nor will any feed-back take place between these two circuits.

The master oscillator circuit is constituted by electron tubes 1 and 2 connected in balanced relationship for sustaining the oscillations of the piezo electric crystal element 9 connected in the common input circuit of tubes 1 and 2 by means of the contact plates 10 and 11.

The balance between the intermediate amplifier and power amplifier is obtained in the following manner: The radio frequency energy used to energize the grids of tubes 5 and 6, being obtained from opposite sides of the filament connection on the inductance 14 is 180 degrees out of phase. Therefore, the energy by-passed by means of the inter-element capacities in tubes 5 and 6, the same being of equal magnitude and diametrically opposite in phase, cancel each other to the end that no energy is fed over and feed-back is eliminated.

The power supply system for the transmitter may be of any desired frequency. I have employed a source of alternating current of a frequency varying between 25 to 1,000 cycles. The power supply line from the alternating current source is brought in from terminals 19 and after passing through main switch 20 is supplied to the primary windings 35 of the several transformers 16, 22 and 25. A circuit breaker 21 is interposed in the primary circuit for the protection of the system. A transformer 22 having secondary winding 23 and primary winding 24 supplies the plate potential for the oscillator tubes 1 and 2. The transformer 25 having secondary winding 26 and primary winding 27 supplies the plate circuits for the frequency multiplier tubes 3 and 4 and the power amplifier tubes 5 and 6. The primary windings 24, 27 and 17 are all supplied from the power source connected at 19. Connections are provided at 28 for measurements of the voltage in various parts of the filament circuits.

50 A resistance R4 is connected between the center or mid tap of the secondary winding 26 of transformer 25 and the key relay 29 from whence the circuit proceeds to the filament or ground through the ammeter A5. 55 When the contacts of the key relay 29 are closed the plate circuits of the frequency multiplier and the amplifier tubes 3, 4, 5 and 6 are completed and plate current flows. This results in a drop of potential over R4. This 60 resulting difference in potential is applied to the grids of the tubes 3 and 4 by means of the connections indicated by 30 and 31. It will be noted that the polarity of the potential applied to the grids is negative with respect to the filaments. By properly selecting

the value of R4 the correct value of potential may be obtained for best operating characteristics.

R3 is a resistance connected between the mid tap of secondary winding 23 of the plate transformer 22, supplying the potential for the master oscillator tubes 1 and 2, and filaments or ground. This arrangement produces the necessary negative grid potential for these tubes. It will be noted that this circuit is not keyed and therefore the tubes are permitted to oscillate continuously, a feature that is necessary, or at least highly desirable, when quartz crystal control is employed.

The contacts of key relay 29 are controlled by winding 32 through a control line 33. When the key contacts are closed, the frequency multiplier and amplifier tubes 3, 4, 5 and 6 receive plate current and the proper grid potentials are automatically established.

Now, as the key contacts 29 are released the action is such that resistance, in the form of key contact resistance is inserted in the lead that connects the center of transformer secondary 26 to ground or filaments. Key 29 when open effects the opening of circuit 26-29-12.

With this increase in resistance the potential drop becomes greater resulting in a greater negative potential being impressed upon the grids. This negative potential or rather the increase of resistance in turn reduces the flow of plate current and by the time the key contacts 29 are actually open, the negative potential on the grids has reached such a magnitude that the grid blocks and plate current ceases to flow. This prevents arcing at the key contacts and results in efficient and clean cut key action.

When the key contacts are actually separated the resistance in the center lead is practically infinite and the negative potential (static potential) impressed on the grids equals in magnitude the voltage developed in the secondary of the plate transformer 25 between the center tap of winding 26 and the extreme end.

The current that flows in the center tap is uni-directional pulsating current and thus the grids are never subjected to positive potentials as in the case where transformers are used to supply grid potentials. Another advantage of this system is that as plate current tends to increase, the drop over the resistance 24 increases with a resulting increase in the negative potential applied to the grids which in turn automatically regulates the plate current.

Hence it will be seen that there is established an automatic compensating action for limiting plate current to desired values.

A line relay 34 is provided for the control of the operation of the transformers through a power switch indicated at 35.

The arrangement of the electron tubes in balanced circuits in the oscillator, the intermediate amplifier and the high frequency power amplifier systems is such that the tend-

ency of parasitic oscillations in the tube circuits interfering with the normal operation of the system is substantially eliminated. The electron tube circuits connected to tubes 5 3 and 4 and to tubes 5 and 6 are so arranged that they operate to increase the amplitude of the signaling energy without the transfer of inherent oscillatory currents in the direction of the piezo electric crystal control element 9.

10 In this way the oscillations developed in the circuits of tubes 1 and 2 under control of the piezo electric crystal element 9 are transferred and impressed upon the power amplifier stages with minimum loss.

15 The balanced system of my invention has been found to be very practical in operation and more efficient than systems of single tube balanced circuits heretofore employed in the art. The several circuits in the transmitter, 20 that is the oscillator, the frequency multiplier circuit, and the power amplifier circuit, are all uniformly arranged in balanced relationship and arranged to prevent reaction of one circuit upon another.

25 While I have described my invention in certain preferred embodiments, I desire that it be understood that modification may be made and that no limitations upon my invention are intended other than are imposed by the 30 scope of the appended claims.

What I claim as new and desire to secure by Letters Patent of the United States is as follows:

35 1. An electron tube transmitter constituted by a plurality of electron tubes connected in separate pairs, each of said tubes having grid, filament and plate circuits connected thereto, a power source of alternating current 40 for energizing the circuits of said electron tubes, said pairs of electron tubes being connected in cooperative balanced relationship for utilizing the effects of the alternating current power source upon the circuits of said 45 electron tubes successively in each tube circuit of each pair of electron tubes, one pair of electron tubes being connected for the generation of high frequency oscillations and another pair of electron tubes being connected for increasing the amplitude of the oscillations 50 thus developed, and an electrostatic coupling between the filaments of the first mentioned pair of electron tubes and the said output circuits of succeeding pairs of electron tubes.

55 2. In a system for the transmission of high frequency radio signals the combination of an oscillator comprising a pair of three-element electron tubes connected in cooperative balanced relationship and having a common output circuit, an amplifier system the input circuit of which is coupled to said output circuit, said amplifier system also comprising paired three-element electron tubes connected in cooperative balanced relationship, an alternating current source to excite the

elements of the tubes in said oscillator and in said amplifier, and an inductance across the plate circuits of said amplifier tubes having condenser-coupled connections to the tube filaments of said amplifier system whereby the 70 radio frequency energy by-passed by the tubes is caused to set up magnetic fields in said inductance which oppose and cancel one another by virtue of the approximate equality of the inter-element capacities in the tubes 75 of the amplifier along with the oppositely phased excitation of the plates of said tubes in each pair while the grids thereof are parallel-connected and the filaments thereof are synchronously excited.

3. In a radio transmitting system the combination of a plurality of stages for generation of oscillations and for amplification comprising a plurality of three-element electron tubes in bilaterally paired arrangement 85 with the grids of each pair parallel-connected, the filaments of each pair parallel-connected and with capacitatively bridged output circuits for each stage, an alternating current source supplying suitable potentials 90 to each of the elements of said tubes and adapted to excite the plate elements thereof alternately as between the tubes of each pair, a tuning circuit in electrically balanced connection with the bridged output circuit for 95 each stage, a load circuit connected to the tuning circuit of the last stage and capacitative couplings between each of said tuning circuits and the filament elements of the preceding stage whereby reaction between successive stages is prevented.
